George Sanford Randall.

GEORGE SANFORD RANDALL, OF PROVIDENCE, RHODE ISLAND.

Letters Patent No. 88,073, dated March 23, 1869; antedated September 23, 1868.

IMPROVEMENT IN CASES FOR MELODEONS, &c.

The Schedule referred to in these Letters Patent and making part of the same.

To all whom it may concern:

Be it known that I, GEORGE SANFORD RANDALL, of Providence, in the county of Providence, in the State of Rhode Island and Providence Plantations, have invented a new and useful Improvement in the Construction of Cases of Musical Instruments, of the class known as reed-organs, "cabinet," "parlor," "cottage," "American," "boudoir," and other styles and kinds of reed-instruments, formerly known as harmoniums and organ-harmoniums, and also portable pipe-organs, under whatever name they may be manufactured; and I do hereby declare that the following is a full and exact description thereof, reference being had to the accompanying drawings, and to the letters of reference marked thereon.

The nature of my invention is as follows:

The construction of organ-cases, of the classes enumerated, with one or more apertures in the form of closets, (either open or closed,) or drawers, either in front or on the ends or back, for the accommodation of music-books, papers, or any other personal property it may be desirable to place therein, for convenience or safe-keeping, thereby utilizing the space formerly unoccupied, as well as furnishing a place for the accommodation of books, papers, &c., at a nominal cost, as compared with that of an article of furniture constructed for any similar purpose.

I am well aware that the instruments above enumerated have been constructed with book-cases, or closets on top of the cases, as, for instance, the style of organs known as the high-top cases, or imitation pipe-organ fronts; but the cost of the same is very much greater than by my method herein described, besides not being applicable to the style of case for which my invention

is intended, being that style known as the low case, or having the top lid within a few inches of the key-boards.

By the use of my invention, the ordinary music-stands, or racks may be dispensed with, unless the parties using the same have an unusual amount of music or books.

By affording this convenience, much of the wear and tear of music will be spared, and it will be kept free from dust and dirt, thereby presenting a cleaner appearance when bound in a book-form.

The best form for constructing the closets, as well as the most convenient, is, in my opinion, that represented by the accompanying drawings.

Figure 1, perspective view of organ-case, with book-cases, as above described.

A, rim, or top case.

B, bottom case.

C, book-case doors.

D, blow-pedals.

E, panel over blow-pedals.

F, dotted lines, outlines of case, as either inserted in the case, or built as a part of it.

G, book-case, with door opened.

H, book-case, door closed.

What I claim as my invention, and what I wish to secure by Letters Patent, is—

The case for musical instruments, constructed with closets on the sides of the bellows-pedals, substantially as and for the purposes as described.

GEORGE SANFORD RANDALL.
